PORTABLE POWER MEGAPHONE

Frederick L. Hardesty, Silver Spring, Md.

Application December 22, 1953, Serial No. 28,168

Term of patent 14 years

(Cl. D26—14)

To all whom it may concern:

Be it known that I, Frederick L. Hardesty, a citizen of the United States of America, residing at Silver Spring, in the county of Montgomery and State of Maryland, have invented a new, original, and ornamental Design for a Portable Power Megaphone, of which the following is a specification, reference being had to the accompanying drawing, forming a part hereof.

Figure 1 is a side elevational view of a portable power megaphone, showing my new design;

Figure 2 is an underside plan view thereof; and
Figure 3 is a rear end view of the same.

The dominant features of my design reside in the portions shown by full lines.

I claim:

The ornamental design for a portable power megaphone, as shown and described.
